UNITED STATES PATENT OFFICE.

KENNETH BINGHAM QUINAN, OF SOMERSET WEST, CAPE PROVINCE, SOUTH AFRICA.

DUST-COLLECTING DEVICE.

1,370,484.

Specification of Letters Patent.

Patented Mar. 1, 1921.

Application filed February 25, 1919. Serial No. 279,117.

To all whom it may concern:

Be it known that I, KENNETH BINGHAM QUINAN, a citizen of the United States of America, and residing at Somerset West, 5 Cape Province, Union of South Africa, have invented certain new and useful Improvements in and Relating to Dust-Collecting Devices, of which the following is a specification.

10 This invention relates to apparatus of the kind in which dust-laden gases are caused to pass through channels which are of small height in relation to their width, for the purpose of facilitating the deposition of the 15 dust from the gases.

In the construction of apparatus of this kind, within a flue or chamber through which the gases are caused to travel a plurality of trays or plates have been arranged 20 horizontally for the purpose of splitting up the current of gas into a number of streams.

As a result of the deposition of dust upon these trays or plates, it is necessary at suitable intervals to interrupt the current of 25 gas through such flues or chambers for the purpose of enabling the dust deposited thereon to be removed.

According to the present invention the trays in question are supported in the flues 30 or chambers in such manner that they may be inclined sufficiently to enable the dust settled upon them to run off the trays. The degree of inclination will depend upon the angle of repose of the material which is 35 caused to settle upon them.

In the construction of an apparatus in accordance with the invention, the trays may be supported along one edge on suitable members adapted to permit the trays to be 40 rocked, while the opposite edges of the trays are connected in a suitable manner to a support which is adapted to be moved in an upward and downward direction, in order to raise the trays into a horizontal position 45 or to cause the trays to be inclined at an angle which will enable the material deposited upon them to run off.

The base of the chamber in which the trays are arranged may be provided with 50 mechanically operated means for causing the dust discharged from the trays to be conveyed from the flue or chamber.

As will be understood, a variety of methods of operating the trays in order to cause 55 them to be raised into their horizontal posi-

tion or to be inclined at a suitable angle may be employed. Conveniently, the trays may be supported at one edge by vertical rods passing through holes in the roof of the chamber and connected in any suitable manner by mechanism adapted to raise or lower these bars by mechanical means or otherwise.

An apparatus in accordance with the invention is illustrated, by way of example, in 65 the accompanying drawings, in which:—

Figure 1 is a cross-section of a dust-settling device.

Fig. 2 is a corresponding plan; and

Fig. 3 is a view illustrating the method 70 of supporting the trays from one wall of the flue.

In the drawings, 1 and 1^a represent the side walls, and 2 the center wall of a pair of flues or chambers, 3 and 3^a representing 75 the inlets for the gases into the chambers, and 4 and 4^a the corresponding outlets therefrom. The chambers are provided with inclined bottoms 5 and 5^a and in the bases of the chambers, troughs 6 and 6^a are arranged 80 for the accommodation of a device adapted to be operated mechanically to withdraw the settled dust or to facilitate the removal of the dust by manual labor by way of the openings 7 and 7^a which will be provided 85 with suitable doors.

Trays 8 are arranged within the flues or chambers, being hinged at 9 to members secured to the center wall, while at their opposite edges they are secured to the bars 10 90 supported by chains 11 secured to drums or equivalent devices arranged on the shafts 12 which are adapted to be rotated in order to raise or lower the trays.

The trays are conveniently formed of relatively thin sheet metal and at their edges they may be formed as shown in Fig. 3 so that portions of such edges encircle the bar 13 which is supported on brackets 14 secured in the flue wall as shown or in any 100 other suitable manner.

As will be understood the details of construction are matters of engineering design and therefore the detailed particulars furnished are given for the purpose of indicating a suitable manner of carrying the invention into effect and are not to be considered as limiting the scope of the invention.

Having now described my invention, what 110

I claim as new and desire to secure by Letters Patent is:—

1. In a dust collector, the combination with a dust chamber having an inlet and an outlet at opposite ends, of a plurality of dust-collecting trays intermediate the said ends, means for pivotally supporting the individual trays adjacent one side wall of the chamber, and means connected with the trays to simultaneously move the trays about their pivots.
2. In a dust collector, the combination with a dust chamber having an inlet and an outlet at opposite ends, of a plurality of dust-collecting trays intermediate the said ends, means for pivotally supporting the individual trays adjacent one side wall of the chamber, means constructed and arranged to hold the trays in parallel relation and to afford a unitary motion of the trays about their pivots, and means for moving the trays about their pivots.
3. In a dust collector, the combination with a dust chamber having an inlet and an outlet at opposite ends, of a plurality of dust-collecting trays intermediate the said ends, means for pivotally supporting the individual trays adjacent one side wall of the chamber, a member pivotally connected to each tray to afford a unitary motion of the trays about their pivots and hold the trays in parallel relation and means connected with said member for moving the trays about their pivots.
4. In a dust collector, the combination with a dust chamber having an inlet and an outlet at opposite ends, of a plurality of dust-collecting trays intermediate the said ends, means for pivotally supporting the individual trays adjacent one side wall of the chamber, a member affording a pivotal support for the individual trays opposite said first pivotal supporting means and holding the trays in parallel relation during pivotal motion and means for raising and lowering said member.
5. In a dust collector, the combination with a dust chamber having an inlet and an outlet at opposite ends, of a plurality of dust-collecting trays intermediate the said ends, means for pivotally supporting the individual trays adjacent one side wall of the

chamber, a member affording a pivotal support for the individual trays opposite said first pivotal supporting means and holding the trays in parallel relation during pivotal motion and means for raising and lowering said member, the trays and said member being so constructed that when the trays are in horizontal position the said member contacts with the other side wall of the chamber.

6. In a dust collector, the combination with a dust chamber having an inlet and an outlet at opposite ends, of a plurality of dust-collecting trays intermediate the said ends, means for pivotally connecting one edge of each tray to one side wall of the chamber, a bracket, means for movably supporting the bracket adjacent the opposite wall of the chamber and a hinge connection between each of the trays and the said bracket.

7. In a dust collector, the combination with a dust chamber having an inlet and an outlet at opposite ends, of a plurality of dust-collecting trays intermediate the said ends, means for pivotally supporting the individual trays adjacent one side wall of the chamber, a bracket element pivotally connected to each tray along the edge opposite to said pivotal support, means for raising and lowering said bracket element, the arrangement being such that when the bracket element is in its highest position it firmly contacts with the other side wall of the chamber and the trays assume a substantially horizontal position.

8. In a dust collector, the combination with a dust chamber having an inlet and an outlet at opposite ends, of a plurality of dust-collecting trays intermediate the said ends, means for detachably supporting the individual trays for pivotal motion adjacent one side wall of the chamber, a bracket element pivotally connected to each tray along the edge opposite to the said side wall and adapted to firmly contact with the other side wall when the trays are in substantially horizontal position and means for lowering the bracket.

In testimony whereof I have signed my name to this specification.

KENNETH BINGHAM QUINAN.
